UNITED STATES PATENT OFFICE.

ROBERT H. SAGENDORPH, OF BROOKLINE, MASSACHUSETTS, ASSIGNOR TO EASTERN EXPANDED METAL COMPANY, OF CAMBRIDGE, MASSACHUSETTS, A CORPORATION OF MASSACHUSETTS.

METAL LATH.

Application filed November 8, 1926. Serial No. 146,880.

This invention relates to metal lath, an object of the invention being to provide an improved lath formed by first slitting and then expanding a metal sheet, and thereafter applying a coating material to the face of the slit and expanded sheet in such manner as to cover predetermined portions of the sheet so as to provide keyways or spaces of considerable less total area than the area of the sheet for retaining the plaster when applied, thereby enabling a very considerable saving in the amount of plaster used.

Objects of this invention will appear in the following description and appended claims, reference being had to the accompanying drawings forming a part of this specification wherein like reference characters designate corresponding parts in the several views.

Fig. 1 is a plan view showing a portion of a sheet of metal lath made in accordance with my invention.

Fig. 2 is an enlarged section taken substantially on lines 2—2, Fig. 1.

Fig. 3 is a section similar to Fig. 2 showing the plaster applied to the lathing to make the finished wall.

Fig. 4 is a plan view illustrating a portion of a sheet of metal lath embodying a modified form of the invention.

Fig. 5 is an enlarged section taken on lines 4—4, Fig. 3.

Fig. 6 is a section similar to Fig. 5 showing the plaster applied to the lathing to make a finished wall of the form of lathing shown in Figs. 4 and 5.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention beyond the terms of the several claims hereto appended or the requirements of the prior art.

In accordance with the present preferred form of my invention the metal lath is first slit and expanded in any suitable machine and in accordance with any preferred system. One form of expanded sheet is shown in Fig.

1 by way of illustration. A coating of pulp or analogous fibrous material is then applied to the expanded sheet. This material when applied is a wet pulpy or plastic mass capable of entering the interstices or spaces A between the spaced strands B of the lath. Wood pulp such as used for paper stock or other fibrous material may be used, and is spread over the lath in a layer so as to be preferably of the thickness of the metal strands as shown in Fig. 2.

Referring to Figs. 1 and 2, the pulp or fibrous material may be applied by means of a suitable press or by feeding the expanded metal sheet between rollers. In this form of the invention, sections C of the sheet are covered or embedded so as to provide intermediate these sections keyways D of suitable width to enable the plaster to be applied to the lath and to cling or to be keyed thereto, as shown in Fig. 3, the layer of plaster being designated M and the keys N. The embedded sections C of the lath will preferably have a slightly greater thickness than the thickness of the portions D so that the layers of fibrous material enclosing the strands of the lath will not only adhere to the latter but also form a continuous strip in which the fibre or pulp throughout its length will be united together, thereby resisting any tendency of the layers of pulp material to become separated from the strands of the lath. In addition it will be noted that the strands B of the lath are positioned edge-wise and in an inclined manner transversely to the plane of the sheet. Therefore when the strands are embedded in the pulp material, the inclined faces of the strands will form a locking means preventing the pulp from being forced out of the spaces A. The inclined position, therefore, of the strands as clearly shown in Fig. 2, enables them to clinch the pulp material in the spaces between the strands, as a result of which the strands of the lath and the pulp material will be firmly united together in the sections or layers C. Moreover, the inclination of the edges of the strands at an angle to the plane of the lathing provides a body or reinforcement for the fibrous material, which is particularly desirable in a construction wherein uncovered areas, such as D, are provided, due to the tendency of such lathing to flex sharply and break down the fibrous body, such as pulp, which, although relatively flex-

ible or non-brittle, as compared to a plaster, should be protected in this or similar manner against sharp deflection. The intermediate uncovered portions D of the metal also having the edges of the strands disposed at an angle to the wall, cooperate effectively with the plaster M and key or clinch the same in position upon the lath, at the same time providing a suitable rigid foundation 10 or reenforcement for the plaster.

Referring to Figs. 4, 5 and 6, the coating of pulp or fibrous material may be first spread over the lath in a continuous sheet so that all of the strands of the lath will be 15 embedded in this material. Thereupon the sheet may be inserted in a press and multiple holes E may be punched out in a single operation, these holes being preferably located centrally of the several apertures or interstices 20 between the strands of the lath. From this construction, it will be noted that the resultant lath product will have the necessary spaces E providing keys to retain the plaster in position, while at the same time the total 25 area of these holes will be considerably less than the total area of the normal spaces between the strands of the lath, thereby enabling a considerable saving of plaster to be had. In Fig. 6 the surface layer of plaster 30 is shown at O and the keys at P.

The pulp or fibrous material which may

be used in the present invention is relatively cheap and may be readily and easily applied by suitable mechanism so that the cost of the lath will not be materially increased. On the 35 other hand the resultant lath is stiffer and has more strength, is easier to handle, and will enable a considerably greater saving in plaster than the additional cost of the lath.

What I claim is:

1. The improved lathing material which comprises a sheet of expanded metal certain areas of which have holes between the strands closed by masses of dry paper stock fibers, the fibers being held in place by enveloping 45 the strands of metal and the remaining areas of the sheet being uncovered to form openings through it.

2. The improved lathing material which comprises a sheet of expanded metal having 50 strands disposed edgewise and angularly relative to the plane of the sheet, certain areas of the sheet having holes between the strands closed by masses of dry paper stock fibers, the fibers being held in place by enveloping 55 the strands of metal and the remaining areas of the sheet being uncovered to form openings through it in which the metal strands are exposed.

In testimony whereof I affix my signature.

ROBERT H. SAGENDORPH.
